[57] CLAIM

The ornamental design for a balance panel for an automobile, as shown and described.

DESCRIPTION

FIG. 1 is a perspective view of a balance panel for an automobile showing our new design;

FIG. 2 is a front elevational view thereof;

FIG. 3 is a rear elevational view thereof;

FIG. 4 is a right side elevational view thereof;

FIG. 5 is a top plan view thereof;

FIG. 6 is a bottom plan view thereof; and

FIG. 7 is a perspective view thereof on a reduced scale, it being understood that the broken lines are for illustrative purposes only and form no part of the design.
